HYDRODESULFURIZATION OF SELECTED GASOLINE FRACTIONS

Henry D. Noll, Philadelphia, Pa., assignor to Houdry Process Corporation, Wilmington, Del., a corporation of Delaware

Filed Dec. 30, 1958, Ser. No. 783,839

2 Claims. (Cl. 208—97)

This invention relates to the treatment of crude oils having a high sulfur content, and particularly to the hydrodesulfurization of gasoline fractions obtained therefrom.

It is well recognized in the petroleum refining art that the presence of sulfur is objectionable in petroleum products generally, and is especially undesirable in motor fuels, such as gasoline, because of its characteristic of impairing the lead response for octane improvement. Furthermore, it has a tendency to form SO_2 , which is both obnoxious and corrosive.

With respect to the hydrodesulfurization of catalytically-cracked gasolines, it has been found necessary to avoid an excessive loss of octane number in reducing the sulfur content to acceptable levels, particularly as a result of olefin saturation. One way in which this has heretofore been accomplished is by selective hydrodesulfurization over particular catalysts under selected conditions with respect to temperature, pressure, space rate and hydrogen-to-oil ratios.

Contained within the catalytically cracked gasoline, however, there are low-boiling olefinic components which readily become saturated under the conditions necessary for removal of those sulfur compounds which are more difficult to remove. It is known that improved hydrodesulfurization may be obtained by subjecting the catalytically-cracked gasoline to fractionation into lower-boiling and higher-boiling fractions, the cut being made in such manner that the former fraction will contain most of the olefins of the gasoline and few sulfur compounds, while the latter will contain relatively few olefins and most of the sulfur compounds. The higher-boiling fraction may then be subjected to hydrodesulfurization treatment at more severe conditions, since it contains relatively few olefins, and the lower-boiling fraction may either not be treated at all or, if its sulfur content is too high, be subjected to hydrodesulfurization treatment at very mild conditions so as to cause a minimum of olefin saturation. The two gasoline fractions are then combined to form a gasoline of acceptable sulfur content with a minimum F-1 clear octane loss due to olefin saturation, and often with an actual gain in F-1 leaded octane for the same lead concentration.

With the development of new refinery processing techniques for converting crude residua to high-quality distillate products, it has been possible to obtain relatively high yields of gasoline, with octane ratings typical of gas-oil catalytic cracking, from residuum cuts ranging from crude-tower bottoms to vacuum bottoms.

However, with residuum cuts of higher sulfur content, it becomes increasingly difficult to effect the desired sulfur removal, even with the aforementioned techniques of separating the catalytically-cracked gasoline into higher-boiling and lower-boiling fractions, with separate hydrodesulfurization treatment of each fraction under different conditions.

In accordance with the present invention, a crude charge stock known to be relatively high in sulfur con-

2

tent, such as a Wafra crude, is processed for maximum total recovery of high octane gasoline suitable for blending into refinery pools by heating to appropriate temperature and subjecting the heated material to a flash separation in order to obtain a lower-boiling straight-run products fraction comprising straight-run gasoline, kerosine and diesel oil and a remaining higher-boiling fraction, generally referred to as topped crude. The light, or low-boiling, fraction is relatively low in sulfur content, while the heavy, or high-boiling, fraction is relatively high in sulfur content.

The topped crude is then catalytically cracked in known manner, and the product vapors are fractionated to produce a low-boiling overhead fraction comprising unstable, light, catalytically-cracked gasoline of low sulfur content, but rich in olefins, a naphtha fraction comprising catalytically-cracked naphtha of low sulfur content, a higher-boiling distillate fraction of high sulfur content comprising catalytically-cracked kerosine and diesel oil and, of course, a bottoms fraction comprising heavy gas oil.

The distillate fraction withdrawn from the fractionator is then combined with the low-boiling, straight-run products fraction resulting from the flash separation of the vaporized crude. Following suitable hydrogen addition, the total mixture is reheated and then subjected to vapor phase hydrodesulfurization treatment in the presence of a cobalt-molybdena-alumina catalyst and under relatively severe reaction conditions. Optionally, these two fractions may be treated individually in separate hydrodesulfurization reactors, under severity conditions suitable to the sulfur content of the particular fraction.

The reaction products of such hydrodesulfurization treatment are then cooled, and the normally gaseous products, including hydrogen and hydrogen sulfide are separated. The separated gaseous product is then freed of hydrogen sulfide in known manner and the sulfur-free gas may then be used as recycle gas, supplemented with fresh make-up hydrogen, if needed.

The liquid product of such separation is fractionated to recover a 275° F. E.P. straight-run gasoline substantially free of sulfur, a light gas overhead, and products heavier than gasoline. Although the gasoline is of relatively low octane, it is nevertheless suitable for blending.

The naphtha fraction of the catalytically-cracked, topped crude is vaporized and then subjected to a selective hydrodesulfurization treatment similar to that employed for treatment of the straight-run gasoline fraction, but at substantially milder conditions, since the naphtha fraction has a low sulfur content. As before, the treated product is cooled and separated. The sulfur, as hydrogen sulfide, is removed in known manner, and hydrogen-containing gas is recovered for recycle purposes. Make-up hydrogen is added, if necessary.

The condensed liquid product of the second hydrodesulfurization treatment may then be stripped to remove a light gaseous overhead which may contain some remaining sulfur components, leaving a heavier liquid portion of desulfurized catalytically-cracked naphtha.

The unstable, light, catalytically-cracked gasoline, which is high in olefin content and low in sulfur content, is then treated in known manner to remove C_3-C_4 and lighter components and the remaining C_5 and heavier components are combined with the catalytically-cracked naphtha to form a 385° F. E.P. catalytic gasoline of relatively high octane.

For a fuller understanding of the invention, reference may be had to the following description and claims, taken in connection with the accompanying drawing forming a part of this invention and showing a typical preferred embodiment thereof.

Referring to the drawing, wherein the general layout of a refinery is diagrammatically illustrated, with omis-

3
sion of various pieces of apparatus not considered necessary to an understanding of the invention, the crude charge stock is supplied through conduit 10.

The charge is heated in furnace 11 and is then passed through conduit 12 to a crude flash tower 13. The overhead from the flash tower, discharging through conduit 14, comprises a fraction composed of gasoline, kerosine and diesel oil.

The topped crude is withdrawn as a bottoms product from flash tower 13 and is passed through a line 15 to a catalytic cracking unit 16. The catalytically-cracked reactor effluent from unit 16 is passed through conduit 17 to a fractionating column 18, commonly referred to as a synthetic crude tower.

The fractionator overhead, withdrawn through conduit 19 comprises all the light gaseous effluent, together with an unstable, light, catalytically-cracked gasoline comprising about 75 wt. percent of the total gasoline in the reactor effluent of the cracking unit 16.

Intermediate cuts of catalytically-cracked naphtha, comprising the remaining approximately 25 wt. percent of the total gasoline, and a distillate comprising catalytically-cracked kerosine and diesel oil are withdrawn at the sides of the fractionator through conduits 21 and 22, respectively. The usual provisions for stripping and overhead reflux are provided for these intermediate cuts. Likewise, an intermediate side stream may be withdrawn, cooled and returned to the tower as reflux. For the sake of simplicity, such side reflux operation is not illustrated. The fractionator bottoms portion is withdrawn through conduit 23 and disposed of as heavy gas oil, or fuel oil product.

The straight-run gasoline, kerosine and diesel oil fraction withdrawn from crude flash tower 13 through conduit 14 is cooled in known manner and is passed to an accumulator or reflux drum 24, from which a fraction of the condensate is continuously returned through conduit 25 to the tower 13 as reflux, while the remainder of the condensed overhead stream, containing straight-run gasoline, kerosine and diesel oil, and having a relatively low sulfur content, is passed into conduit 26 for conveyance to a furnace 27.

The distillate fraction withdrawn as a side stream from fractionator 18 through conduit 22, and having a relatively high sulfur content, is introduced into conduit 26 containing the straight-run products fraction of low sulfur content from flash tower 13. The stream flowing to furnace 27 will therefore have a sulfur content intermediate to that of the individual combining streams. As the mixed stream flows through conduit 26 to furnace 27, hydrogen is added as part of a sulfur-free recycle gas stream supplied through conduit 28, from a source herein-after to be described, or, if needed, as fresh make-up hydrogen supplied through conduit 29.

The mixture of straight-run and catalytically-cracked hydrocarbons and hydrogen heated in furnace 27 is conveyed therefrom by conduit 31 into a hydrodesulfurization reactor 32 containing a bed of cobalt-molybdena-alumina catalyst 33. The introduced hydrocarbons are in vapor phase, and pass downwardly through the bed 33 while converting the sulfur compounds to hydrogen sulfide. The vaporous reactor effluent is withdrawn at the bottom of the reactor 32 through conduit 34, is cooled by conventional heat exchange, and is passed as a mixed-phase stream to a separator or flash drum 35.

The separated vaporous material, containing the sulfur as hydrogen sulfide, is passed from flash drum 35 through conduit 36 to a scrubber 37 of known design wherein the hydrogen is recovered for recycle purposes and discharged through conduit 28.

The separated sulfur-free condensate is removed from flash drum 35 through conduit 38 and is passed to a distillate products splitter or fractionator 39.

The light overhead products from fractionator 39 are 75

withdrawn through conduit 41, cooled to condense the gasoline fraction, and then passed into the separator or flash drum 42. The separated gaseous effluent is sent to fuel gas supply through conduit 43, a portion of the condensed gasoline product is returned to fractionator 39 through conduit 44 as reflux, and the remaining straight-run gasoline is discharged through conduit 45.

A side cut comprising kerosine and jet fuel is withdrawn from fractionator 39 through conduit 46, is stripped, and then cooled; and a lower side cut comprising diesel oil is withdrawn through conduit 47, is stripped, and then cooled.

The bottoms fraction is withdrawn from fractionator 39 through conduit 48 and, after cooling, is sent to fuel oil storage.

The light straight-run gasoline from conduit 45, either alone or in combination with the fraction from conduit 46, is then stabilized in known manner to recover product straight-run gasoline having a 275° F. E.P.

20 The light overhead product discharged from fractionator 18 through conduit 19 is cooled and passed to a separator, or flash drum 51. The separated gaseous effluent is discharged through conduit 52, while the liquid condensate, comprising an unstable, light, catalytically-cracked gasoline is in part returned to fractionator 18 through conduit 53 as reflux, but in major part discharged through conduit 54. The wet gaseous effluent in conduit 52 and the light catalytic gasoline in conduit 54 are subjected to conventional treatment for removal of ethane, methane and hydrogen, which go to fuel gas, and for removal of C₃ and C₄ hydrocarbons, which go to liquefied petroleum gas. Such treatment is diagrammatically designated at 55.

35 The catalytically cracked naphtha withdrawn from fractionator 18 through conduit 21 is passed to a heater 56. As in the case of the straight-run gasoline, kerosene, and diesel oil stream passing through conduit 26, the stream in conduit 21 is supplied with recycle hydrogen from conduit 28 and with fresh make-up hydrogen, as needed, through conduit 57.

40 From heater 56, the hydrogen-containing-naphtha stream is passed through conduit 58 to hydrodesulfurization reactor 59, containing a bed of cobalt-molybdena-alumina catalyst 61. The type of treatment carried out in reactor 59 is similar to that in reactor 32, except that milder conditions may be employed in reactor 59 because the treated material is relatively low in sulfur content. The effluent from reactor 59 is withdrawn through conduit 62, cooled, and separated in separator or flash drum 63. 45 The separated gaseous material, containing sulfur as hydrogen sulfide, is removed from flash drum 63 through conduit 64 and is introduced into conduit 36 leading to the scrubber 37.

50 The separated, catalytically-cracked and desulfurized naphtha is withdrawn from flash drum 63 through conduit 65 and is passed to a conventional stripper 66 which removes the light gaseous material as an overhead stream through conduit 67. After cooling and returning the condensed liquid material to the stripper as reflux, the 55 gaseous material goes to fuel gas.

55 The remaining desulfurized catalytically-cracked naphtha is withdrawn through conduit 68. The gasoline product from treater 55 is withdrawn through conduit 69 and is mixed with the gasoline product from stripper 66 to form a 385° F. E.P. catalytically-cracked gasoline of relatively high octane value, which is suitable for blending with the 275° F. E.P. straight-run gasoline in conduit 45.

60 Describing a typical operation in accordance with the invention, wherein all stated percentages will be based upon the crude, the charge stock received through conduit 10, heated in furnace 11 and charged to the crude flash tower 13 is, for example, a "Wafra" crude, familiar to those engaged in oil refining operations. The specific charge of Wafra crude is found to contain about 3.84 65 wt. percent of sulfur.

The flash tower overhead admitted into conduit 26 for conveyance to the hydrodesulfurization reactor 32 comprises the following components in the stated proportion: 6 vol. percent of 275° F. E.P. gasoline containing .09 wt. percent of sulfur, 9.5 vol. percent of kerosine containing .40 wt. percent of sulfur, and 19.5 vol. percent of diesel oil containing 1.90 wt. percent of sulfur.

The topped crude withdrawn from flash tower 13, which is catalytically-cracked in cracking unit 16 and then fractionated in tower 18, yields, among other things 3.6 vol. percent of catalytically-cracked naphtha containing 1.20 wt. percent of sulfur and a catalytically-cracked distillate fraction comprising 3.2 vol. percent of kerosine containing 2.0 wt. percent of sulfur and 7.1 vol. percent of diesel oil containing 3.8 wt. percent of sulfur.

The catalytically-cracked distillate fraction is withdrawn from fractionating tower 18 and is conveyed through conduit 22 to conduit 26, where it joins the stream of flash tower overhead. Hydrogen-containing gas and/or hydrogen is supplied to conduit 26 in such amount as to provide therein a hydrogen/oil mol ratio of about 3 to 1, which amount may be expressed in terms of about 1950 s.c.f./bbl. The admixture is then heated and, in vaporized or partially vaporized state, is introduced into hydrodesulfurization reactor 32 at a space rate (vol. oil/hr./vol. cat.) in the order of about 2.0. The inlet temperature and pressure of reactor 32 are about 700° F. and 750 p.s.i.g., respectively.

The reaction products from reactor 32, recovered in the manner herein described, comprise fuel gas, H₂S, 6.0 vol. percent of 275° F. E.P. gasoline containing .01 wt. percent of sulfur, 12.6 vol. percent of kerosine containing .05 wt. percent of sulfur, 26.0 vol. percent of diesel oil containing .37 wt. percent of sulfur, and 0.9 vol. percent of fuel oil containing .67 wt. percent of sulfur.

The catalytically-cracked naphtha fraction withdrawn from fractionating tower 18 through conduit 21 for conveyance to the selective hydrodesulfurization reactor 59 is likewise admixed with hydrogen-containing gas and/or hydrogen to provide a hydrogen/oil mol ratio of about 3 to 1. This admixture is then heated and in vapor phase is introduced into reactor 59 at a space rate vol. oil/hr./vol. cat. in the order of about 2.0. The inlet temperature and pressure of reactor 59 are about 650° F. and 300 p.s.i.g., respectively.

The reaction products from reactor 59, recovered in the manner herein described, comprise fuel gas, H₂S, and 3.6 vol. percent of catalytically-cracked naphtha containing .04 wt. percent of sulfur.

It is to be understood that the foregoing is illustrative of a single preferred operation in accordance with the invention and that the conditions maintained in both the hydrodesulfurization reactor 32 and the selective hydrodesulfurization reactor 59 may vary to some extent. Thus, it is contemplated that in reactor 32 the space rate may be in the range of 0.5 to 10, the inlet temperature may be in the range of 650-800° F., the pressure may be in the range of 600-1000 p.s.i.g., and the hydrogen/oil mol ratio may be in the range of 1/1 to 5/1. In reactor 59, the space rate may be in the range of 1.0 to 50, the temperature may be in the range of 500-750° F., the pressure may be in the range of 200-700 p.s.i.g., and, again, the hydrogen/oil mol ratio may be in the range of 1/1 to 5/1.

By the method of this invention it is possible to process high-sulfur crude charge stocks for the recovery of useful petroleum products relatively free of sulfur. For the purpose of this invention a high-sulfur crude may be considered one containing sulfur in an amount equivalent to 1 to 5, or even greater, weight percent.

With respect to the recovery of gasoline as one of the useful end products of the process, the invention makes possible the recovery of straight-run and catalytic gasoline of low sulfur content and relatively high octane value. This is achieved primarily through the feature of separately hydrodesulfurizing selected portions of the flash-

separated and catalytically-cracked materials under different severity conditions. Under this arrangement, it is possible to hydrodesulfurize under relatively mild conditions that portion of the sulfur-rich catalytic gasoline fraction which is most susceptible to undesirable hydrogenation of olefinic and aromatic constituents, whereby these constituents may be retained to the greatest possible extent, consistent with the necessary sulfur removal, for octane improvement and increased lead response in the ultimate gasoline product. Since hydrogenation of the hydrocarbons is to be minimized in the treatment of the catalytic gasoline fraction containing unsaturates readily susceptible to hydrogenation, not only may the reaction conditions be substantially milder in the reactor handling

15 the latter fraction, but the catalyst may be one which does not too readily promote the hydrogenation reaction. Thus, it is possible to use in the latter reactor either a different catalyst or the same type of catalyst after it has become partially spent.

20 As an alternative to the arrangement of processing equipment herein described and illustrated, it is contemplated that the fraction of catalytically cracked material withdrawn from fractionator 18 through conduit 22 may be sent to a separate hydrodesulfurization reactor, 25 instead of being combined with the material in conduit 26 and being treated in reactor 32. Also, that the gaseous materials withdrawn from separators 35 and 63 may be treated in separate units 37 for removal of sulfur instead of in a common unit as shown.

25 Obviously many modifications and variations of the invention as hereinbefore set forth may be made without departing from the spirit and scope thereof, and therefore only such limitations should be imposed as are indicated in the appended claims.

30 35 What is claimed is:

1. In a hydrocarbon conversion process for the treatment of a crude charge stock of high sulfur content, wherein said charge stock is initially separated into a low-boiling straight-run products fraction comprising 40 straight-run gasoline, kerosene and diesel oil and a topped crude fraction and wherein said topped crude fraction is catalytically cracked and then fractionally distilled to recover a bottoms fraction comprising heavy gas oil and a catalytic products fraction consisting of the components 45 boiling lower than said heavy gas oil, the method for removing sulfur from both said straight-run and catalytic products fractions preliminary to further treatment thereof for ultimate recovery of desired end products, which method comprises the steps of: further fractionating said 50 catalytic products fraction to separate therefrom a naphtha fraction in the gasoline boiling range, leaving a gasoline-free distillate fraction of relatively high sulfur content including catalytically cracked kerosene and diesel oil; combining said distillate and straight-run products fractions; 55 adding hydrogen-containing gaseous material to said combined fractions in a hydrogen/oil mol ratio of between about 1/1-5/1 and subjecting the resultant mixture to relatively severe hydrodesulfurization treatment in the presence of cobalt-molybdena-alumina catalyst at a space 60 rate in the range of about 0.5-10, at a vapor inlet temperature of about 600-800° F. and at a pressure of about 600-1000 p.s.i.g.; cooling the effluent of said hydrodesulfurization treatment and removing therefrom gaseous 65 products containing hydrogen sulfide, thereby obtaining for said further treatment a desulfurized liquid product comprising straight-run naphtha, kerosene and diesel oil.

2. In a hydrocarbon conversion process for the treatment of a crude charge stock of high sulfur content, wherein said charge stock is initially separated into a low-boiling straight-run products fraction comprising straight-run gasoline, kerosene and diesel oil and a topped crude fraction, and wherein said topped crude fraction is catalytically cracked and then fractionally distilled to recover a bottoms fraction comprising heavy gas oil and 75 a catalytic products fraction consisting of the compo-

7
nents boiling lower than said heavy gas oil, a method for refining said catalytic products fraction which comprises the steps of: further fractionating said catalytic products fraction into a light gasoline fraction, containing the major portion of the total catalytic gasoline, and a heavy catalytic gasoline fraction of relatively low sulfur content, leaving a gasoline-free distillate fraction of relatively high sulfur content including catalytically cracked kerosene and diesel oil; adding hydrogen-containing gaseous material to said heavy catalytic gasoline fraction in a hydrogen/oil mol ratio of between 1/1-5/1 and subjecting the gaseous material-gasoline fraction to relatively mild hydrodesulfurization treatment in the presence of cobalt-molybdena-alumina catalyst at a space rate in the range

5 of about 1.0-50, at a vapor inlet temperature of about 500-750° F. and at a pressure of about 200-700 p.s.i.g.; cooling the effluent of said hydrodesulfurization treatment and removing therefrom gaseous products containing hydrogen sulfide, thereby obtaining a desulfurized liquid product comprising heavy catalytically-cracked gasoline.
